UNITED STATES PATENT OFFICE.

SYLVESTER EASTMAN, OF PROVIDENCE, RHODE ISLAND, ASSIGNOR TO THE
SYNCHRONOUS TIME COMPANY OF PORTLAND, MAINE.

CLOCK-PENDULUM.

SPECIFICATION forming part of Letters Patent No. 337,384, dated March 9, 1886.

Application filed May 18, 1885. Serial No. 165,828. (No model.)

To all whom it may concern:

Be it known that I, SYLVESTER EASTMAN, of Providence, county of Providence, State of Rhode Island, have invented an Improvement 5 in Regulators for Clocks and other Apparatus, of which the following description, in connection with the accompanying drawings, is a specification, like letters on the drawings representing like parts.

10 This invention has for its object to provide the pendulum-rod of a clock or other apparatus employing a pendulum with a spring-supported weight or bob, and suitable regulating devices co-operating therewith, whereby 15 the weight or bob may be raised or lowered by and against the tension of the said spring, thus affording very accurate and minute adjustment.

15 The invention consists of a pendulum-rod 20 provided with a weight or bob, combined with a spring interposed to support the said weight or bob; and a regulating device co-operating therewith for positively moving the said weight or bob vertically upon the pendulum- 25 rod.

20 The weight or bob is hereina shown as bored centrally, and the pendulum-rod, encircled by a spiral spring, is passed therethrough, the upper end of the said spring bearing against an 30 annular or other suitable projection or shoulder within the weight or bob, while its opposite end bears against a suitable nut screwed to the lower end of the pendulum-rod.

25 The regulating device consists in this instance of a gear-wheel turning on a screw-threaded portion of the pendulum-rod, and meshing with a pinion to the arbor of which is secured a thumb-nut, rotation of the pinion causing the gear-wheel to be turned on the 35 pendulum-rod, and co-operating with the spring, as will be hereinafter more fully described, raising and lowering the weight or bob.

35 Figure 1 shows in vertical section a pendulum-bob constructed in accordance with this 40 invention, the pendulum-rod being broken off and the regulating device being shown in elevation; Fig. 2, a top view thereof; Fig. 3, a modification to be referred to, and Fig. 4 a cross-section of Fig. 1 on the dotted line *xx*.

45 50 The pendulum-rod *A*, of usual construction,

is provided with a weight or bob, *B*, of cylindrical shape, said rod *A* passing axially through the weight or bob *B*, which is bored for such purpose. A spiral spring, *b*, encircles the pendulum-rod *A* within the weight or bob *B*, the lower end of which bears against a thumb-nut, *d*, screwed to the lower end of the said pendulum-rod, while its upper end, bearing against an annular projection or shoulder, *c*, integral with and near the upper end of the central passage of the weight or bob, supports the latter, the spring being of sufficient strength to become but slightly compressed while thus resisting the gravitating force of the said weight or bob. 65

The regulating device consists in this instance of a gear-wheel, *e*, placed within an annular recessed portion at the upper end of the weight or bob *B*, said gear-wheel having an internally-threaded hub, *a*, turning upon a screw-threaded portion, *f*, of the pendulum-rod *A*, the lower face of the said hub bearing against the upper end of the weight or bob *B*. This gear-wheel *e* meshes with a pinion, *g*, having an arbor, *h*, to which is rigidly secured a thumb-nut, *i*, for rotating the same. A cap or cover, *m*, is placed upon the top of the weight or bob *B*, covering the recessed portion thereof, bearing upon the upper face of the hub *a* of the gear-wheel *e*, and serving 80 as a bearing for the arbor *h*, thus concealing all the operating parts, with the exception of the thumb-nut *i*.

The operation of the apparatus is as follows: The parts being as shown in Fig. 1, it is assumed that the spring *b* is compressed both by the gravitating force of the weight or bob *B* and by the hub *a*, which has been screwed down somewhat on the thread *f*. The thumb-nut *i*, rotated in the direction of the arrow, Fig. 2, will, by its connected pinion, meshing with the gear-wheel *e*, turn the latter upon the screw-threaded portion *f* of the pendulum-rod *A*, and the hub *a*, bearing against the cover *m*, co-operating with the tension of the spring, 90 will raise the weight or bob *B*, but if rotated in the opposite direction will cause the spring to be compressed. The thumb-nut *i* is preferably provided with pointers or indicators *i'*, which co-operate with a graduated scale, *i''*, 100

to indicate divisions of time, as a second or fraction thereof, so that the extent of rotation of the pinion g may be determined accurately when it is desired to raise or lower the weight or bob B to adjust the clock or other apparatus to exact time. A complete rotation of the thumb nut i in engagement with the gear-wheel will turn the latter on the pendulum-rod for but a partial rotation, and by providing the screw-threaded portion with many threads to the inch the weight or bob B may be raised or lowered but a very little, and consequently by only a very small part of a revolution of the thumb-nut the weight or bob B will have given to it but very little movement, thus enabling very nice and accurate adjustment to be effected. The thumb-nut d may also be turned to adjust the tension of the spring as may be desired.

Should it be desired to apply the regulator to a pendulum-rod having the ordinary bob attached, it may be placed above the bob, as shown in Fig. 3, serving as a supplemental weight, the parts necessarily being constructed on a smaller scale; the operation, however, being the same.

I do not desire to limit my invention to the exact means shown and described for positively raising and lowering the weight or bob B , as other suitable devices may be employed with good results.

It is obvious that the spring b may be omitted—as, for instance, in small weights or bobs—and the regulating device be operated to positively raise and lower the same; and it is also obvious that, referring to Fig. 3, the regulating devices may be omitted and the supplemental weight or bob be supported by the spring alone, and thereby moving independently of the pendulum-rod, serving as a compensating-pendulum.

I claim—

1. The threaded pendulum-rod and its movable weight or bob, combined with a spring to support said weight or bob, and with a gear having a threaded hub in engagement with the screw-thread of the said rod, and co-operating with the said spring to raise or lower the weight or bob, substantially as described.

2. The pendulum-rod and weight or bob moving vertically thereon, combined with a spring to support the said weight or bob, and the gear-wheel turning on a screw-threaded portion of the pendulum-rod, and means to rotate the said gear-wheel to positively raise and lower the weight or bob, substantially as described.

3. The threaded pendulum-rod and weight or bob loose on the said rod, a spring to support the said weight or bob, and a gear-wheel, e , having its threaded hub a turning on the screw-threaded portion of the rod, combined with the pinion g and the nut i , all substantially as described.

4. The pendulum-rod, the spring supported weight or bob thereon, the gear-wheel, and means to move it, combined with an indicating device, substantially as described.

5. The threaded pendulum-rod and the weight or bob thereon, combined with the gear having a threaded hub in engagement with the screw-threads of the said rod, the pinion g , meshing with said gear, and the nut i , substantially as described.

In testimony whereof I have signed my name to this specification in the presence of two subscribing witnesses.

SYLVESTER EASTMAN.
